(57) **CLAIM**

The ornamental design for a vehicle steering wheel lock, as shown and described.

DESCRIPTION

FIG. 1 is a perspective view of a vehicle steering wheel lock showing our new design;

FIG. 2 is a front plan view thereof;

FIG. 3 is a back plan view thereof;

FIG. 4 is a right side view thereof;

FIG. 5 is a left side view thereof;

FIG. 6 is top view thereof; and,

FIG. 7 is a bottom plan view thereof.

Broken lines showing in the drawings of a vehicle steering wheel lock form no part of claimed design.
